CLAIM

The ornamental design for a display panel of computer system with animated graphical user interface as shown.

DESCRIPTION

FIG. 1 is a first view of a first embodiment of a display panel of computer system showing an animated graphical user interface design;

FIG. 2 is a second view thereof;

FIG. 3 is a third view thereof;

FIG. 4 is a fourth view thereof; and,

FIG. 5 is a fifth view thereof.

The appearance of the transitional image sequentially transitions between the images shown in FIGS. 1-5. The process or period in which one image transitions to another forms no part of the claimed design.

(Continued)

The broken line showing of a display panel with animated graphical user interface in FIGS. 2, 4, and 5 are included for the purpose of showing portions of the article which forms no part of the claim.

1 Claim, 5 Drawing Sheets
